UNITED STATES PATENT OFFICE

WILLIAM F. KIESEL, JR., OF HOLLIDAYSBURG, PENNSYLVANIA

FREIGHT CAR

Application filed March 7, 1931. Serial No. 520,798.

This invention has particular relation to freight cars and especially to gondola cars, the invention being characterized by the provision of a corner member in the form of an angular casting, one arm of which is adapted to serve as an end post forming the terminus of a side truss, and the other arm of which is adapted for attachment to the car center sill to form an end sill thereon.

10 The primary object of the invention is to provide improved means at the corner of a car for connecting the end of a side truss with the center sill, and by making such connecting means in the form of an integral casting, including therein various parts which heretofore have constituted separate attachments, to lighten the car structure and to reduce the labor involved in its assembly without sacrifice in strength or rigidity.

Other objects and advantages characterizing my invention will become more fully apparent from the detailed description hereinafter of one example of the invention, the description having reference to the accompanying drawings, whereof:

Fig. I is an end view of a gondola car embodying my invention.

Fig. II is a side elevation of one end of the car.

Fig. III is a plan view of the same.

Fig. IV is a longitudinal sectional view of the end of the car showing the adaptation of the end gate for use as a bridge supported at one end on the end sill of the car and provided at this end with a special form of attachment engaging a flange of the end sill to limit the outward movement of the end gate.

Fig. V shows a modified form of attachment for the end gate to facilitate its use as a bridge in the manner shown in Fig. IV.

Fig. VI is an enlarged end view of a corner casting generally similar to that shown in Fig. I but modified to facilitate the attachment of hand brake gear.

Fig. VII is a side elevation of the hand brake corner casting shown in Fig. VI.

50 Fig. VIII is a cross section of the hand

brake corner casting taken as indicated by the lines VIII—VIII of Fig. VI; and

Fig. IX is a cross section of the hand brake corner casting taken as indicated by the lines IX—IX of Fig. VI.

The car selected for illustration in the drawings is a relatively long low sided gondola car, the general features of which are described in my co-pending application for U. S. Letters Patent, Serial No. 520,797, filed March 7, 1931. That portion of the car which is here illustrated comprises generally a center sill 1, side trusses and corner castings 3 and 4 joining the ends of the side trusses with the center sill 1. The center sill 1 is built up, according to common practice, of a pair of longitudinal beams 5 with outwardly extending top and bottom flanges 6 and 7 and a casting 8 secured to the beams 5 at their ends. Housed within the center sill beams 5 there is shown the usual draw bar 9 with a coupler 10 at the end thereof.

Each corner casting 3, 4 comprises a vertical arm 11 constituting an end post forming the terminus of a side truss and a horizontal arm 12 joined to the top of the center sill and constituting a part of an end sill for the car body. Each casting 3, 4 is substantially of box shaped section relatively strong at the corner or bend and decreasing in thickness from the corner or bend towards the ends of the arms 11 and 12, the diminishing thickness being more pronounced in the horizontal arm 12 which terminates in a narrow ledge 13 with an inclined surface fitting against and riveted to a top flange 6 of a center sill beam 5.

The vertical arm of each corner casting 3, 4 is formed at the top with a horizontal ledge 14 supporting the web 15 of a Z-bar 16 which forms the top chord of a side truss. Adjacent to the ledge 14 there is a recess 17 which is formed to receive the downturned flange 18 of the Z-bar 16. A flange 19 extending longitudinally of the car from an inner side of the vertical arm of each corner casting 3, 4 is riveted to the end of a side wall 20. An additional flange 21 extending transversely of the car from an inner side of the vertical arm 11 serves as an abutment or

seat against which the end gate designated at 22 rests when the gate is in its normal position. This flange 21 is provided with an opening at 23 to permit the end gate 22 to be used as a bridge in a manner as hereinafter described. At its bottom end the flange 19 of each vertical arm 11 is offset as shown at 24 to provide a recessed area for accommodating the end of a bottom chord 25 of a side truss. In the present example of my invention there is also riveted to the bottom of the vertical arm 11 a side step 26; and above the side step there is provided a ladder comprising rungs 27 attached by rivets at their ends to a bracket 28 on the one side and to perforated bosses 29 on the other side which bosses are cast integrally with the corner member.

The horizontal arm 12 of each corner casting 3 includes an inwardly projecting floor flange 30 to which the floor plates 31 of the car are riveted, and an upstanding flange 46 which acts as an abutment against which the end gate 22 rests. Vertical ribs 57 serve to brace or stiffen the upstanding flange 46 and the floor flange 30. At the corner the floor flange 30 joins the inwardly extending vertical flange 58 of the corner post. Within each horizontal arm 12 there is a cavity at 2 bounded at its ends by vertical webs 32, serving as hinge legs, with elongated diagonal apertures 33 as clearly shown in Fig. VIII. The cavity 2 is of such size as to receive therein the arms 34 of a U-shaped link 35. The links 35 are pivoted to the corner castings 3, 4 by means of a bolt 36 which passes through the slotted webs 32 and the expanded ends of the link arms 34 and which may be retained in place by a pin 37. The links 35 are in turn attached by means of brackets 38 to the end gate 22, and they serve in effect as demountable hinges permitting the end gate to be swung downward to the car floor or to be removed as desired. When the end gate 22 is in its normal position, it is held in place at the top by means of pivoted latches 39 which engage brackets 40 riveted to the top of the corner castings 3, 4. The end gate may be released at the top by swinging the latches 39 upward about the U-shaped bolts 41 as pivots.

At one side of the car, the corner casting 3 is formed with an angular protuberance 42 extending downward at the corner which protuberance affords a bearing for the free end of a coupler operating rod 43. The coupler operating rod is engaged between opposite lugs 44 formed thereon and is restrained against outward movement by a cotter pin 45. By forming the lugs 44 integrally with the corner member 3, the necessity of resorting to a separate attachment for supporting the free end of the coupler operating rod 43 is eliminated.

When it is desired to use the end gate 22

as a bridge to span the space between the end of the car and a platform or the floor of another car, this may be accomplished as shown in Fig. IV, by first detaching the end gate at top and bottom, and then sliding it in a horizontal position outward from the car floor. The end gate will be permitted to pass through the openings 23 in the flanges 21 of the vertical arms 11 of the corner castings 3, 4 and will rest upon the flanges 46 of the horizontal arms 12. In this position the bottom of the end gate becomes the outer end of the bridge, and the links 35 which normally act as hinges may conveniently be used as handles. The top of the end gate which becomes the inner end of the bridge is preferably provided with clips 47 which are adapted to catch upon the edge of the flange 46 and thus limit the movement of the bridge in an outward direction; or the end gate may be provided with a modified form of clip 47a, as shown in Fig. V of U-shaped section with legs 48 and 49 serving as stops on each side of the flange 46.

In Figs VI and VII, there is shown a modified form of corner casting 3a designed for use at a hand brake corner. The casting includes a vertical arm 11a and a horizontal arm 12a substantially similar to the arms of the corner castings herein described. At the corner, however, the casting 3a is provided with an opening 50 adapted to accommodate a bell crank lever forming part of the brake rigging. To afford a fulcrum for the bell crank lever on the walls 51 adjacent to the opening 50, machined bosses 52 with holes 53 therethrough are provided near the top of the opening 50. On the vertical arm 11a, there are additional openings 54 and a machined surface 55 with a plurality of holes 56, this arrangement facilitating the attachment of various parts of the hand brake rigging.

It will be particularly noted that the corner members 3, 4 and 3a are substantially complete in themselves and require a minimum of separate attachments to be applied thereon when the car is assembled. Furthermore, the vertical arms 11 being configured to receive the ends of the top and bottom chords and webs of the side trusses, and the horizontal arms 12 being joined to the center sill, the stresses imposed upon the side trusses are directly communicated at the car corners through the corner castings. When superimposed loads are carried on the top chords of the side trusses, outward bending of the vertical arms 11 of the corner members is resisted by the engagement of the ledges 13 of the horizontal arms 12 beneath the projecting top flanges 6 of the center sill.

While I have described my invention with reference to an embodiment thereof in a particular type of freight car, and while I have referred at some length to the details of a

preferred form of corner casting, it will be apparent that various changes may be made in the arrangement as herein described and that certain features of the invention may be used to advantage without a corresponding use of other features.

Having thus described my invention, I claim:

1. In a railway car, a center sill, a side truss, and a corner member in the form of an angle having a vertical arm formed with flanged and recessed portions adapted to receive the end of the side truss and constituting an end post, and having a transversely extending horizontal arm with its inner end terminating at the center sill and secured thereto. 10
2. In a railway car, side trusses, a gate at the ends of said side trusses, and corner members having vertical portions secured to said side trusses and forming end posts and having transversely extending horizontal portions forming an end sill, said corner members having flanges serving as abutments for holding the end gate in position. 20
3. In a railway car, a corner member in the form of an angle having one arm adapted to serve as an end post and another arm adapted to serve as an end sill, said corner member being substantially reinforced at the bend and decreasing in thickness towards the ends of said arms. 30
4. In a railway car, a center sill, and a corner casting in the form of an angle having a vertical arm adapted to serve as an end post for a side truss and a horizontal arm joined to said center sill, said horizontal arm having a protuberance thereon extending downward at the corner and formed to afford a bearing for a coupler operating rod. 40
5. In a railway car, a center sill, and a corner casting in the form of an angle having a vertical arm adapted to serve as an end post for a side truss and a horizontal arm joined to said center sill, said horizontal arm having opposite lugs formed thereon affording a bearing for a coupler operating rod. 45
6. In a railway car, corner castings in the form of angles having vertical arms adapted to serve as end posts for side trusses and horizontal arms adapted to serve as an end sill, said legs having flanges affording abutments for holding an end gate in position with recessed areas in said flanges permitting the end gate to be passed therethrough when used as a bridge. 50
7. In a railway car, a removable end gate, corner castings having vertical and horizontal flanged arms adapted to serve respectively as end posts and parts of an end sill with their flanges affording abutments for the end gate, each said vertical arm having a recessed area immediately above the flange of a horizontal arm whereby the end gate may be passed 60
- through said corner castings when used as a bridge supported on the end sill. 10
8. In a railway car, a removable end gate, corner castings having vertical and horizontal flanged arms adapted to serve respectively as end posts and parts of an end sill with their flanges affording abutments for the end gate, the flanges of said vertical arms having recessed areas permitting the passage of the end gate therethrough when used as a bridge, and the end gate having a clip thereon adapted to catch upon the flanges of said horizontal arms when the end gate is used as a bridge. 70
9. In a railway car, an end post comprising a casting of substantially box shaped section formed at top and bottom to accommodate the ends of top and bottom chords of a side truss, and having a longitudinal flange adapted for attachment to the side wall of the car, said casting having a projecting boss thereon adapted to receive one end of a side ladder rung. 80
10. In a railway car, an end post comprising a casting adapted for attachment to the end of a side truss and including a projecting perforated boss affording a seat for the end of a side ladder rung. 90
11. In a railway car, an angular corner member of substantially box shaped section having a vertical arm forming the terminus of a side truss and a horizontal arm constituting an end sill. 95
12. In a railway car, a flanged center sill, and a corner member in the form of an angle having one arm adapted to serve as an end post, and having another arm with a ledge at the end thereof engaged beneath a flange of the center sill and joined thereto. 100
13. In a railway car, a flanged center sill, an angular corner member having a vertical arm forming the terminus of a side truss, and a transversely extending horizontal arm formed at its end to fit against a flange of said center sill and being attached thereto. 105
14. In a railway car, an end post of substantially box-shaped section formed at its top to accommodate a side truss top chord in the shape of a Z-bar and recessed at the inner side near the bottom to accommodate a side truss bottom chord in the form of a vertically disposed flat plate, said post having a longitudinally extending flange adapted for attachment to the said wall of the car. 110
15. In a railway car, a center sill, and an angular corner member of substantially box-shaped section comprising a vertical arm forming the terminus of a side truss, and a horizontal arm joined at its end to the center sill, said horizontal arm decreasing in thickness towards the center sill. 120
16. In a railway car, a center sill, a side truss, and a corner member of substantially box-shaped section and in the form of an angle having a vertical arm secured to the end of the side truss and constituting an end 125

post, and having a transversely extending horizontal arm secured to the center sill and constituting an end sill, said corner member having an opening therein adapted to house parts of the hand brake gear of the car.

17. In a railway car, a center sill, a side truss, and a corner member of substantially box-shaped section and in the form of an angle having a vertical arm secured to the end of the side truss and constituting an end post, and having a transversely extending horizontal arm secured to the center sill and constituting an end sill, said corner member having an opening therein and perforated walls adjacent to said opening affording a fulcrum for a brake lever.

18. A one-piece metal car end casting comprising a corner post and a horizontal arm, and apertured hinge lugs arranged on said arm.

19. A one-piece metal car end casting comprising a corner post and a horizontal arm, said arm having a floor flange projecting inwardly therefrom and braced by ribs.

20. A one-piece metal car end casting comprising a corner post and a horizontal arm, said post being provided with an inwardly extending vertical flange, a horizontal floor flange projecting inwardly from said arm and joined to the flange of the corner post, and ribs reinforcing said floor flange.

In testimony whereof, I have hereunto signed my name at Altoona, Pennsylvania, this 25th day of February, 1931.

33 WILLIAM F. KLESEL, JR.
